POTHEAD DEVICE

George P. Edmonds, Chicago, Ill., assignor to
G & W Electric Specialty Co., Chicago, Ill., a
corporation of Illinois

Application January 8, 1930, Serial No. 419,278

18 Claims. (Cl. 173—353)

This invention relates to electrical conductors in general, and more particularly to pothead devices such as are used for connecting electrical cables and overhead conductors.

6 Pothead devices usually include a tubular insulation member of porcelain for receiving an electrical cable, an inlet device connected to the porcelain at the inlet end thereof for closing the same and embracing the cable, and a device at the 10 outlet end for closing the same and for forming a contact whereby the cable may be electrically connected to the overhead conductor. It is highly desirable to connect these inlet and outlet devices to the porcelain in such a manner that 15 the connection will withstand rough usage and will be substantially air tight. Various means have been provided in the past for connecting these inlet and outlet devices to their respective ends of the porcelain insulator member. In order 20 that no leakage may occur at either the inlet or outlet ends, it is desirable that these devices be connected to the porcelain without relative rotation therebetween as that would cause an unevenness in any gasket that might be used.

25 The primary object of this invention is to provide inlet or outlet devices for potheads, and connections therefor to the porcelain of the pothead, wherein no cement is used and wherein no relative rotation occurs between the various devices and 30 the porcelain.

Another object of this invention is to provide an improved construction of pothead and inlet and outlet devices which can be economically manufactured and assembled and which is readily 35 accessible for inspection, renewal or repair.

Other and further objects of this invention will 40 be apparent as the same becomes better understood from an examination of the specification and claims in connection with the accompanying 45 drawings, wherein;

Fig. 1 is an elevation of a pothead embodying this invention;

Fig. 2 is a vertical section of the same;

Fig. 3 is a horizontal section taken at the line 45 3—3 of Fig. 2;

Fig. 4 is a vertical fragmentary section of a modification;

Fig. 5 is a horizontal section taken at the line 50 5—5 of Fig. 4;

Fig. 6 is a vertical fragmentary section of a modification;

Fig. 7 is a horizontal section taken at the line 55 1—1 of Fig. 6.

Referring to the drawings more particularly, reference character 1 designates a tubular in-

sulator member provided with an opening 2 at its upper end and an opening 3 at its lower end for the reception of an electrical cable, the upper end of which is shown at 4. The insulator member is provided with a plurality of peripheral 5 longitudinally spaced dielectric baffles 5.

The cable is embraced at the inlet end of the pothead device through the intermediary of a hollow cylindrical inlet fitting 6 connected to the inlet end of the insulator member 1. The lower 10 end of the fitting 6 is provided with an inwardly tapered portion 7, the innermost end of which is adapted to embrace the cable.

The outer periphery of the tubular member 1 near its inlet end is provided with a circular 15 groove 8 which forms a circular shoulder 9. The lower end of the tubular member 1 forms a circular shoulder 11 which engages the face 12 of a flange 13 integrally formed on the upper end of the fitting 6 through the intermediary of a 20 gasket 14. A ring 15 surrounds the lower end of the insulator member 1 and has its inner periphery cut to provide a similar internal diameter at its upper end and a larger internal diameter at its lower end. The ring 15 is provided 25 with an internal circular shoulder 16 separating the two inner peripheral portions of different diameters. This shoulder 16 is in engagement with the upper outer edge of a snap ring 17 seated in the groove 8 in engagement with the shoulder 9. 30 A plurality of circularly arranged longitudinally extending bolts 18 extend through the flange 13 and are threaded into the ring 15 to draw the shoulder or face 12 of said flange against the shoulder 11 of the insulator member without 35 any rotational relative movement between the fitting 6 and said insulator member, thereby compressing the gasket 14 without danger of causing any unevenness therein.

In assembling, the ring 15 is first slipped over 40 the inlet end of the insulator member 1 beyond the groove 8. The snap ring 17 is then slipped over the inlet end and allowed to snap into place in the groove. The ring 15 is then lowered and is prevented from being withdrawn by the snap 45 ring. The fitting 6 may then be bolted to the ring 15 for attaching said fitting to the insulator member. The fitting 6 is integrally connected to a bracket 19 which may be bolted to a suitable support for the pothead. 50

The upper end of the cable 4 is in the form of a hollow plug 21 which fits in a suitable socket in the lower end of a terminal member 22. This terminal member acts to electrically connect the end of the cable to a contact member 23 which 55

fits over an annular cover member 24 and cooperates therewith to form the cover for the pothead, said terminal member being provided with a threaded extension 25 which extends upwardly beyond the tubular member 1 and is threaded to said contact 23. A gasket 26 is preferably provided on the upper end of the member 24 for sealing the connection between the contact member 23 and said upper end as the contact member is threaded on the terminal member 21 to draw a shoulder 27 on the latter against an internal shoulder 28 on the member 24. The insulator member 1 is connected at its upper end to the fitting, including the member 24, in substantially the same manner that it is connected at its inlet end with the fitting 6, a ring 29 being provided similar to the ring 15 and bolts 31 for attaching the member 24 to said ring. A snap ring 32 seated in the circular groove 33 at the outlet end of the tubular member 1 acts to prevent withdrawal of the ring 29 as the bolts 31 are tightened. In this case also during assembly the ring 29 is first placed over its respective end of the tubular member 1, the snap-ring thereafter snapped into the groove 33 to prevent withdrawal of said ring 29, and the member 24 is then bolted to said ring 29 to compress gasket 33 without relative rotation of the parts on either side thereof.

In Figs. 4 and 5 there is shown a device which is substantially the same as that in the previous embodiment, the only exception being that the snap rings here designated as 34 and 35 are of circular cross section, whereas the corresponding snap rings 32 and 17 of the previous embodiment were of rectangular cross section. In this modification also the walls of the grooves in the insulator member for these snap rings are rounded instead of flat and the walls of the shoulders formed on the rings corresponding to the rings 29 and 15 are round instead of flat.

In Figs. 6 and 7 there is shown a modification wherein instead of using rings such as the rings 29 and 15 of the first embodiment, and instead of using snap rings for preventing the withdrawal of these rings, the upper and lower ends of the insulator member here designated as 36 are provided with circular flanges 37 and 38, respectively. The upper fitting here designated as 39 is exactly the same as in the first embodiment and the lower fitting here designated as 41 is exactly the same as in the first embodiment. Rings here designated as 42 and 43 corresponding to the rings 29 and 15, respectively, in the first embodiment, are made in two parts so that they may be positioned to bring shoulders 44 and 45, respectively, in engagement with the inner face of the corresponding flange on the insulator member and the respective fittings thereafter bolted to their corresponding rings.

It will be apparent that the aforescribed connections for the fittings on the inlet and outlet ends of the pothead not only facilitate assembly and accessibility of the parts, but also prevent interference with the evenness of the gaskets used.

Other advantages of the aforescribed construction will be apparent without further description.

I am aware that many changes may be made without departing from the principles of this invention. I, therefore, do not wish to be limited to the details shown or described.

I claim:

1. In a device of the character described, the combination of a tubular insulator member

adapted to receive a cable therein and provided with an annular shoulder at one end, an annular connecting member adapted to be slipped over said end past said shoulder, an annular contractile member also adapted to be slipped over said end to engage said shoulder and prevent the withdrawal of said connecting member, a fitting on the end of said insulator member adapted to be connected to said connecting member, and means for drawing said fitting and connecting member together for attaching the fitting to the insulator member without relative rotation therebetween.

2. In a device of the character described, the combination of a tubular insulator member adapted to receive a cable therein and provided with an annular shoulder at one end, said insulator member being provided with a second shoulder spaced from the first shoulder, an annular connecting member adapted to be slipped over said end past said shoulders, an annular contractile member also adapted to be slipped over said end to engage the second shoulder and prevent the withdrawal of said connecting member, a fitting on the end of said insulator member, and means for drawing the fitting and connecting member together for attaching the fitting to the annular member without relative rotation therebetween, the planes of said shoulders being normal to the axis of the tubular member.

3. In a device of the character described, the combination of a tubular insulator member adapted to receive a cable therein and provided with an annular shoulder at one end, an annular connecting member adapted to be slipped over said end past said shoulder, an annular contractile member also adapted to be slipped over said end to engage said shoulder and prevent the withdrawal of said connecting member, and a fitting on the end of said insulator member connected to said connecting member by means of longitudinally extending bolts.

4. In a device of the character described, the combination of a pothead member, a readily attachable and detachable engaging ring engaging said member, a connecting ring arranged to act upon said engaging ring, and means for acting upon said connecting ring to cause it to act upon the engaging ring.

5. In a device of the character described, the combination with a hollow pothead member, of a readily attachable and detachable engaging ring having engagement with said member, a connecting ring engaging said engaging ring, and means for drawing upon the connecting ring.

6. In a device of the class specified, the combination with a pothead member, of a snap ring having engagement with an end portion of a pothead member, a connecting ring having engagement with the snap ring, and bolts for acting upon the connecting ring and drawing it against the snap ring.

7. In a device of the class specified, the combination with a pothead member, of a snap ring having engagement with an end portion of a pothead member, a connecting ring having engagement with the snap ring, bolts for acting upon the connecting ring and drawing it against the snap ring, and a plate engaging the other ends of said bolts and also engaging the pothead member.

8. In a device of the character specified, the combination of a pothead member having an end portion provided with a shoulder, a snap

- ring adapted to fit over the pothead end and against said shoulder, a connecting ring also adapted to fit over the end of the pothead and against one side of the snap ring, and means 5 for drawing upon said connecting ring, said means comprising bolts and means for engaging the bolts.
9. In a device of the class described, the combination of a tubular insulator member having one end portion provided with an annular groove, a snap ring adapted to snap into said groove, a connecting ring adapted to engage the inner side of said snap ring, a plate adapted to fit against the end of the tubular insulator, and 10 bolts passing through the peripheral portion of the plate and into the connecting ring and engaging the latter.
10. In a pothead device, a hollow body portion, a series of peripheral longitudinally spaced baffles formed thereon, the body portion extending beyond the said baffles and being provided with a shoulder, a fitting mounted at the end of the said extending portion, and a metallic locking member adapted to engage said shoulder, and means for holding the said fitting and locking member in position without being permanently fixed thereon, said means being disposed outwardly of and in spaced relation to said shoulder.
11. In a pothead device comprising a hollow body portion, a series of peripheral longitudinally spaced baffles formed thereon, the body portion extending beyond the said baffles at each end thereof, each of the said extending portions being grooved and forming a circumferential flange; a two-part ring embracing the said circumferential flange and a fitting bolted to the said two-part ring, the bolts for said fitting and two-part ring being disposed outwardly and in spaced relation to said flange.
12. In a pothead device comprising a hollow body portion, a series of peripheral longitudinally spaced baffles formed thereon, the body portion extending beyond the said baffles at each end thereof, each of the said extending portions being grooved and forming a circumferential flange; a two-part ring having an inwardly extending flange arranged to occupy the said groove and engaging the circumferential flange, 45 and a fitting disposed adjacent said circumferential flange, and means disposed outwardly and in spaced relation to said circumferential flange for connecting said fitting to said ring.
13. In a pothead device comprising a hollow body portion, a series of peripheral longitudinally spaced baffles formed thereon, the body portion extending beyond the said baffles at each end thereof, each of the said extending portions being grooved and forming a circumferential flange; a two-part ring having an inwardly extending flange arranged to occupy the said groove and engaging the circumferential flange,
- and a flange fitting having means for engaging the two-part ring and securing it in position, said means being disposed outwardly and in spaced relation to said flange.
14. In a pothead device comprising a hollow body portion, a series of peripheral longitudinally spaced baffles formed thereon, the body portion extending beyond the said baffles at each end thereof, each of the said extending portions being grooved and forming a circumferential flange; a two-part ring having an inwardly extending flange arranged to occupy the said groove and engaging the circumferential flange, flanged fittings arranged to close each end of the said hollow body portion and bolts to secure the said fittings to each of the said two-part rings in their relative positions, the bolts for said fitting and two-part ring being disposed outwardly and in spaced relation to said flange.
15. In a pothead device comprising a hollow body portion, closure fittings for the upper and lower ends of the said body portion, means readily attachable and detachable with said body portion for retaining said fittings in position; the upper fitting comprising a bolting flange, a central apertured hub portion offset from the plane of the said flange and a frusto-conoidal section connecting the said hub and the said flange, the said upper fitting arranged to receive and support the terminal of said cable.
16. In a pothead device comprising a hollow body portion adapted to contain a cable, closure fittings for the upper and lower ends of the said body portion, means readily attachable and detachable with said body portion for retaining said fittings in position; the upper fitting comprising a bolting flange, a central apertured hub portion offset from the plane of the said flange and a frusto-conoidal section connecting the said hub and the said flange, the said upper fitting arranged to receive and support the terminal of said cable.
17. In a device of the character described, the combination with a hollow pothead member having an annular shoulder provided on one end, a connecting ring adapted to fit over the shouldered end of the pothead member and be engaged therewith, a fitting adapted to be connected to said connecting ring, and means disposed outwardly of said pothead member for drawing said fitting and connecting ring together without relative rotation therebetween.
18. In a device of the character described, the combination of a pothead member, an annular ring having means thereon for being connected with said pothead member without the use of cement, a connecting device adapted to be connected to said annular ring, and means disposed outwardly of said pothead member for drawing the connecting device and annular ring together without relative rotation therebetween.

GEORGE P. EDMONDS.
